SHOULDER STRAP PAD FOR A GOLF BAG OR SIMILAR ARTICLE

Brian W. Lake, 4636 Seebayar Ave., and Roger T. Williams, 4158 Josie Ave., both of Lakewood, Calif.

Filed Aug. 5, 1963, Ser. No. 76,112

Term of patent 14 years

(Cl. D3—26)

FIG. 1

FIG. 2

FIG. 3

FIG. 4

FIG. 5

FIGURE 1 is a top plan view of a shoulder strap pad for a golf bag or similar article, showing the present design; FIGURE 2 is a bottom plan view thereof; FIGURE 3 is a side elevational view thereof; and FIGURE 4 is an end elevational view thereof; and FIGURE 5 is a cross-section taken on the line 5—5 of FIGURE 3 and showing the double thickness of the material at the top.

We claim:

The ornamental design for a shoulder strap pad for a golf bag or similar article, substantially as shown and described.
